UNITED STATES PATENT OFFICE.

GEORGE PARKER, OF BAY CITY, MICHIGAN.

DEVICE FOR THROTTLING STEAM-ENGINES.

SPECIFICATION forming part of Letters Patent No. 313,365, dated March 3, 1885.

Application filed July 23, 1884. (No model.)

To all whom it may concern:

Be it known that I, GEORGE PARKER, of Bay City, in the county of Bay, and State of Michigan, have invented new and useful Improvements in Devices for Throttling Steam-Engines; and I do hereby declare that the following is a full, clear, and exact description thereof, reference being had to the accompanying drawings, which form a part of this specification.

This invention relates to certain new and useful improvements in steam-engines, whereby the engine can be throttled instantly when desired or in case of necessity.

15 The invention consists in the peculiar construction, combination, and operation of certain attachments to the throttle-valve of a steam-engine, which, for instance, when the whistle usually employed on manufacturing 20 establishments is blown for the noon-hour will instantly throttle down the engine by means of a wire connection between the devices for throttling and the whistle, and such wires may be laid to various parts of the mill, so 25 that in case of accident in any part thereof the wire may instantly be pulled, which will cause the engine to be throttled.

The invention further consists in providing means for taking steam from the valve-case as 30 soon as the steam has been cut off from the engine to a brake-cylinder, by means of which a brake may be brought into operation to stop the motion of any heavy machinery where it may be necessary to employ such brake.

35 Figure 1 is a perspective view of the attachment to the throttle-valve stem, showing the attachment to the steam-whistle and to the brake-cylinder. Fig. 2 is a horizontal central section through the throttle-valve and case. Fig. 3 is a vertical cross-section through the valve and case on line $x-x$ in Fig. 2.

In the accompanying drawings, which form a part of this specification, A represents the steam-pipes connecting with the throttle-valve 45 case B, and C is the throttle-valve within such case, secured to the valve-stem D, which projects through a proper stuffing-box, E, from the case, and upon the outer end of the stem D there is rigidly secured a lever, F, to one end of which is secured the counterbalance-weight G. This 50 lever terminates in a handle, H, at the opposite

end, and is provided with a spring-latch, I, operated by the bell-crank lever J and a spring, K, in the usual manner. This latch I engages, as shown in Fig. 1, with a notch in the 55 disk L, which in the drawings is shown as two coincident disks, while in practice a single disk will be found equally effective. This disk is secured by means of the arms M M' to the valve-case in any desired or suitable way. 60

To the arm M' is pivotally secured the cam-lever N, to the free end of which is secured a rope or wire, O, which leads to the whistle, which is usually placed on top of or outside the mill. This wire is secured, when leading 65 to the whistle, to the lower lever or arm, P, which actuates the valve of the whistle Q, so that when this arm is actuated to blow the whistle such arm will actuate the cam-lever N and force the latch I from its engagement with 70 the notch of the disk L, thereby releasing the lever F, when the counter-balance G will cause the valve in the case to partially rotate and throttle the engine. If desired, other wires or ropes may lead from the free end of the cam-lever N to different parts of the mill, so that 75 in case of accident, and it becomes necessary to immediately shut down the engine, the pulling of any of these connections will operate the throttle as described. It might happen 80 that a heavy piece of mechanism might be running at a high rate of speed at the time the engine was throttled as above described, and it becomes necessary to stop the motion of such machine, or a shaft over which it was driven. 85

Consequently I provide a small steam-port, a, in the end of the valve-case, to which I attach a small steam-pipe, b, the bore of which is preferably smaller than the port to which it is attached, in order to "wire-draw" the steam as it passes 90 to the brake-cylinder c, which latter may be of any of the known constructions operating the brake d of any desired pattern. This port a is opened and closed by a gate, C', attached to the valve-stem, and so arranged and located 95 with relation to the throttle-valve that when the latter cuts off steam from the engine it discloses the port a.

I am aware of the Patent No. 36,699, and make no claim to the construction shown 100 therein as forming part of my invention.

What I claim as my invention is—

1. In combination with the throttle-valve of a steam-engine the valve-stem of which is provided with a counter-balance and detent, a retaining-point for the same connected to and carried by the valve-case, and an oscillating lever, as N, also connected to and carried by the valve-case, and constructed and arranged to disengage the detent from the retaining-point, as and for the purposes specified. 20
2. In a throttle-valve the case of which has pipes, as A, branching therefrom, and provided with a supplementary port, as a, the combination of a brake-cylinder connected with said valve-case, with the valve-stem D, valve C and gate C', attached thereto, substantially as shown and described, to open a passage-way through the pipes A and simultaneously close the port a, as and for the purposes specified. 25
3. The combination of the case B, throttle-valve C, and stem D with the lever F, carrying the weight G, the latch I, disk L, cam-lever N, and connection O, the parts being constructed, arranged, and operating substantially as and for the purposes described. 30
4. The combination of the case B, throttle-valve C, and stem D with the lever F, carrying the weight G, the latch I, disk L, cam-lever N, connection O, port a, pipe b, and brake-cylinder c, the parts being constructed, arranged, and operating substantially as and for the purposes specified. 35
